UNITED STATES PATENT OFFICE

ANDRU G. PAPPADAKIS, OF DETROIT, MICHIGAN

ALARM MECHANISM

Application filed February 6, 1929. Serial No. 337,944.

This invention relates to a new and improved alarm mechanism, particularly of the type that sounds an alarm during the rotation of the knob of a door lock.

5 It is the object of this invention, among other things, to provide simple and effective mechanism of this character, wherein the alarm elements are arranged so as to be placed in either an operative or inoperative position and no alarm will sound when in the inoperative position; a further object being to adapt this mechanism for use on a door lock that may be attached to a moving body, such as an automobile or the like, and 15 in these and other ways to simplify, improve and make more effective the mechanism of a device of this character.

To these and other ends, my invention consists in the alarm mechanism having certain 20 details of construction and combinations of parts, as will be hereinafter described and more particularly pointed out in the claims.

In the drawings, wherein like characters of reference indicate like parts in the several 25 figures;

Figure 1 is a view of a lock having my improvement associated therewith, the cover thereof being removed and the interior mechanism partly in section;

30 Figure 2 is a view of a lock with a portion of a door associated therewith, the parts in section being taken generally upon line 2—2 of Figure 1;

Figure 3 is a transverse sectional view, 35 taken generally upon line 3—3 of Figure 1;

Figure 4 is a detail view of one of the latches in its retracted position;

Figure 5 is a transverse sectional view thereof, taken generally upon line 5—5 of 40 Figure 2;

Figure 6 is a detail view of a portion of the lock case, taken generally upon line 6—6 of Figure 1;

Figure 7 is a perspective view of the rock 45 arm;

Figure 8 is fragmentary sectional detail view of the mechanism for holding one of the latches against movement;

Figure 9 is a detail view of one of the 50 latches in its retracted position;

Figure 10 is detail sectional view of a portion of the lock, taken generally upon line 10—10 of Figure 1; and

Figure 11 illustrates my improved mechanism as adapted for use upon the door of a 55 moving car, such as a motor vehicle or the like.

The bell and the particular mechanism for striking the same are of the same general type as is shown in Letters Patent No. 1,632,499, issued to me June 14, 1927, and consist essentially of a bell 10 mounted upon a post 11, upon which is loosely mounted the hammer carrier 12, held against axial movement by the collar 63 and upon which are 60 mounted the hammers 13 with a free lateral movement.

Slidably mounted within the lock case 14 is a latch 15 secured to the outer end of rods 16, which are joined at their rear ends by 70 a tail piece 17 having outwardly flaring arms 18 thereon and provided with a recess 19 in its lower edge which by its engagement with the rib 20 on the lock case is held in proper alignment and against lateral displacement.

Between the tail piece 17 and the fixed plate 21 is operatively mounted the hub 22 upon the spindle 23 rotated by knobs 24 of any preferred form upon the outer ends 80 thereof. This hub is provided with wings 25, which are in substantially the same plane and contact with the outwardly flaring arms 18 of the tail piece 17 so that rotation of the spindle 23 in either direction will move the 85 latch 15 to its retracted position and the springs 26 on the rods 16 will return the same to its out position as soon as rotary pressure on the spindle 23 is released.

A rib 28 on the lock case projects inwardly 90 from the face plate 27 and supports the latch 15 in alignment with the opening in the face plate particularly while moving to and from its retracted position.

Fixed to one of the wings 25 is a sector 29, 95 the teeth of which mesh into those of a sector 30 rotatably mounted upon the post 11.

Rotatably mounted upon the post 31 fixed in the lock case is a gear 32 having formed thereon a pinion 33, the teeth of which mesh 100

into those of the sector 34 integral with the sector 30 but having a larger radius. The teeth of the gear 32 mesh into those of a pinion 35 forming part of the hammer 12.

5 A spring 36 bears against one face of the gear 32 and applies lateral pressure thereto in one direction.

10 Rotation of the spindle 23 when the teeth of the pinion 33 are in mesh with those of the sector 34 rotates the hammer carrier 12, and the hammers 13, thrown out by centrifugal force, strike the inside of the bell or projections thereon and sound the alarm.

15 When the teeth of the pinion 33 are disengaged from those of the sector 34, as shown in Figure 2, rotation of the spindle 23 will not actuate the hammer carrier 12, and hence no alarm will be sounded.

20 The gear 32 is moved axially and the teeth of the pinion 33 disengaged from those of the sector 34 by moving the gear 32 on the post 31 against the tension of the spring 36. This is accomplished through a slide 37 having a yoke end 38 with a slightly tapered upper 25 face 39 which straddles the post 31 and projects under the pinion 33. This slide 37 is movably connected with one end of a rock arm 40 which is mounted in a lug 41 on the screw 42. Pivotaly connected to opposite 30 ends of the rock arm are the push buttons 43 and 44, which project through openings in the face plate 27 and in their out positions are substantially flush with the face thereof and in their in positions are substantially flush with the inner face thereof, as 35 shown in Figure 1. The openings through which the push buttons 43 and 44 project are counterbored for the more ready manual actuation of the push buttons in a manner well known in the art.

40 To prevent accidental movement of the slide 37 the rock arm is held under pressure in its extreme positions by means of a rounded end button 45 that is moved in one direction 45 by a spring 46 held and tensioned by a screw 47 and contacting with the angular faces 48 on the rock arm, which are joined at their inner ends by the ridge portion 49. Pressure of the spring 46 is sufficient to hold 50 the rock arm 40 against accidental movement but not to prevent its manual movement, during which time the button 45 rides on one of the angular faces 48 and over the top of the ridge 49. This cannot be accomplished 55 except when pressure is applied to the rock arm through either of the push buttons 43 and 44.

60 When the slide 37 is moved outwardly through manipulation of the push button 43 the spring 36 moves the gear 32 along the post 31 so that the teeth of the pinion 33 are returned into engagement with those of the sector 34.

65 Heretofore the hammer carrier disengaging mechanism was operated adjacent to the

post supporting the hammer carrier with the result that when out of engagement with its operative mechanism it is free to move except as the same may be held by the tension of a spring. This ordinarily is not sufficient to prevent the rotation of the hammer carrier and the hammers 13, from striking the bell, if the lock is associated with a moving body, such as an automobile or the like. Hence, such mechanism is not adapted for 70 a lock used for this latter purpose because the rattle and annoyance caused by a free hammer carrier.

75 With my improved mechanism the hammer carrier is never free to rotate because it is held by the pinion 35 and gear 32 and the disengaging means is not associated with the hammer carrier directly or with the post upon which it is supported. Therefore, there are no free or rotating parts in my improved 80 mechanism, which is therefore adapted for use with locks on moving vehicles.

85 In Figure 11 is shown the arrangement of the gears when particularly adapted for use on a lock for a motor vehicle or the like, wherein a handle 50 is substituted for the door knob and a sector 51 substituted for the sector 29, which in their inoperative positions are associated substantially as shown in Figure 10, so that movement of the handle 90 95 50 actuates the latch 15.

95 As the handle 50 to open the door moves in only one direction, the sectors 51 and 34 can operate their full length and give more rotation to the hammer carrier and hence a longer alarm.

100 The latch 52 is mounted and supported in substantially the same manner as the latch 15 by the rib 53 and operated through a hub 54, the wings 55 of which engage a tail piece 56 associated with the rods 57. The latch 52 is moved in one direction through manipulation of a key 58 through the hub 54 in a well known manner and may be locked against movement in either its in or out positions as may be desired.

105 The latch 52 is actuated from the inside of the door by a button 59 journaled in a fixed collar 60 and held against endwise movement therein by a retaining screw 61 or the like, which projects into an annular groove in the button 59. On the lower end of this button 59 are lugs 62, which project into a recess 73 in the collar 63, rotatably mounted in the lock case and having wings 64 thereon, which 110 engage the tail piece 56 and provide means for manipulating the latch 52. This latch is held in either its in or out positions by a plug 65 axially and rotatably mounted in the button 59 through the button 66 thereon.

115 In Figure 5 the end of the plug 65 is below the top of the tail piece 56 and thus prevents movement of the latch 52 by the key 58 or otherwise.

120 To lock the latch in its retracted position 125

the plug 65 is moved downwardly so that one wall rests against the face of the button 67 on the tail piece 56. In such position it is held against accidental movement by a pin 68 fixed in the plug, which projects into a slot 69 in the button 59, and engages a shoulder 70 therein under the tension of a spring 71. A slight rotation of the button 66 disengages the pin 68 from the shoulder 70 and the spring moves 10 the plug axially and out of the path of the tail piece 56. When the plug is moved manually in a reverse direction, the pin 68 engages the angular wall 72 of the slot and rotates the plug slightly so as to move the pin 68 under the shoulder 70. When the button 66 is then 15 released the spring 71 moves the plug so that the pin 68 engages and is held against said shoulder.

As designed and constructed the button 59 20 and associated parts are conveniently connected with the lock and separated therefrom by reason of the intermeshing engagement of the lugs 62 with the recess 72 in the collar 63.

The door lock is shown as set in the edge of 25 the door, but it may be applied and will operate equally as well if set in one side of the door or attached to such side.

There are minor changes and alterations 30 that may be made within my invention and I would therefore have it understood that I do not limit myself to the exact construction herein shown and described but claim all that falls fairly within the spirit and scope of the appended claims.

35 What I claim as new and desire to secure by Letters Patent, is:—

1. In a device of the character described, 40 having a case; a latch; means for actuating the latch; an alarm mechanism having an operative connection therewith and set in motion by the latch actuating means, comprising a bell, a hammer to strike the bell, and a gear upon that side of the bell opposite the latch and having a geared connection with the latch 45 actuating means; and a manually controlled slide for shifting the position of the gear relative to that of the hammer and still maintain its operative connection therewith, whereby the hammer actuating means is disconnected from the latch actuating means and the alarm mechanism rendered inoperative.

2. In a device of the character described, 55 having a case; a latch; means for actuating the latch; an alarm mechanism having an operative connection therewith and set in motion by the latch actuating means, comprising a bell, a hammer to strike the bell, and a gear upon that side of the bell opposite the latch and having a geared connection with the 60 latch actuating means; and a manually controlled slide for shifting the position of the gear relative to that of the hammer and still maintain its operative connection therewith, whereby the hammer actuating means is disconnected from the latch actuating means

and the alarm mechanism rendered inoperative, said slide being exposed for operation through the same face of the case as the latch, whereby the alarm mechanism may be rendered inoperative only when the lock is in such 70 position as to expose said face.

3. In a device of the character described, 75 having a case; a latch; means for actuating the latch; a bell; a hammer to strike the bell; a sector movable about an axis coincident with that of the hammer; a geared connection between the latch actuating means and the sector; a gear actuated by the sector and imparting movement to the hammer; and means for moving the position of the gear relative to the sector, whereby the operative connection therebetween is separated and the hammer is held against rotation by means of said gear.

4. In a device of the character described, 80 having a case; a latch; means for actuating the latch; an alarm mechanism having an operative connection therewith and set in motion by the latch actuating means, comprising a bell, a hammer to strike the bell mounted so as to rotate but held against axial movement; a geared connection between the latch actuating means and said hammer means for moving one of said gears, whereby the same is rendered inoperative during the movement of the other of said gears at the same time 85 maintaining its contact with said hammer actuating means.

5. In a device of the character described, 90 having a case; a latch; means for actuating the latch; an alarm mechanism having an operative connection therewith and set in motion by the latch actuating means, comprising a bell, a hammer to strike the bell, and a gear upon that side of the bell opposite the latch and having a geared connection 95 with the latch actuating means; a manually controlled slide for shifting the position of the gear relative to that of the hammer and still maintain its operative connection therewith, whereby the hammer actuating means is disconnected from the latch actuating means and the alarm mechanism rendered inoperative, said slide being movably connected with a rock arm; and means for holding 100 said rock arm against accidental movement in some of its positions, the pressure of which will not be sufficient to prevent movement thereof.

6. In a device of the character described, 105 having a case; a latch; means for actuating the latch; an alarm mechanism having an operative connection therewith and set in motion by the latch actuating means, comprising a bell, a hammer to strike the bell, and a gear upon that side of the bell opposite the latch and having a geared connection 110 with the latch actuating means; a manually controlled slide for shifting the position of the gear relative to that of the hammer and still maintain its operative connection therewith, whereby the hammer actuating means is disconnected from the latch actuating means

with, whereby the hammer actuating means is disconnected from the latch actuating means and the alarm mechanism rendered inoperative, said slide being movably connected with a rock arm, said rock arm having angular faces thereon; a member associated with a fixed part and having contact with said angular faces; and spring means for holding said member against said angular faces under pressure sufficient to prevent the accidental movement of the rock arm but without preventing manual movement thereof.

7. In a device of the character described, having a case; a latch; means for actuating the latch, comprising in part a sector; an alarm mechanism having an operative connection therewith and set in motion by the latch actuating means, comprising a bell and a hammer to strike the bell; a gear sector having two geared portions, each with a different radius, the teeth of one portion being in mesh with the first mentioned sector and the teeth of the other portion being in mesh with a pinion associated with the gear, whereby movement of the latch actuating means imparts rotation to the gear, which in turn controls the movement of the hammer.

8. In a device of the character described; a case having a rib thereon; a face plate forming part thereof; a movably mounted latch, which in one of its positions projects outside of the face plate; means for actuating the latch; and means for holding the latch in alignment with the opening through the face plate, comprising a member associated therewith having an intermeshing engagement with said rib.

9. In a device of the character described; a case having a rib thereon; a face plate forming part thereof; a movably mounted latch, which in one of its positions projects outside the face plate; means for actuating the latch, said latch being supported throughout its entire movement by said rib.

10. In a device of the character described; a case; a latch movably mounted therein; and abutment means for locking said latch in either or both its in or out positions, said means comprising a reciprocating member manually actuated in one direction from outside the lock case and spring actuated in the other direction; and means for holding the same against premature movement when in its position.

11. In a device of the character described; a case; a latch movably mounted therein; and abutment means for locking said latch in either or both its in or out positions, said means comprising a reciprocating member manually actuated in one direction from outside the lock case and spring actuated in the other direction; and means for holding the same against premature movement when in

its in position, said means comprising in part a member associated therewith that travels through a slot in a fixed part and engages a shoulder in one wall thereof.

In testimony whereof, I have hereunto affixed my signature.

ANDRU G. PAPPADAKIS.
